UNITED STATES PATENT OFFICE.

ALFRED E. BRUNS, OF NEW YORK, N. Y., ASSIGNOR TO METAL PACKAGE COMPANY,
OF BROOKLYN, NEW YORK, A CORPORATION OF NEW YORK.

DESIGN FOR A TAPERED OVAL TALCUM-POWDER CAN.

45,447.

Specification for Design.

Patented Mar. 24, 1914.

Application filed May 15, 1913. Serial No. 767,925. Term of patent 7 years.

To all whom it may concern:

Be it known that I, ALFRED E. BRUNS, a citizen of the United States, residing at Brooklyn, New York city, in the county of Kings and State of New York, have invented a new, original, and ornamental Design for a Tapered Oval Talcum-Powder Can, of which the following is a specification, reference being had to the accompanying drawings, forming part thereof, in which—

Figure 1 is a front elevation of a talcum powder container, showing my new design. Fig. 2 is a side elevation of the same. Fig. 3 is a plan.

I claim:

The ornamental design for a tapered oval talcum powder can, as shown.

ALFRED E. BRUNS.
